UNITED STATES PATENT OFFICE.

JOHN HJALMAR LINDROOS, OF BROOKLYN, NEW YORK.

SHIP STRUCTURE.

1,417,260.

Specification of Letters Patent. Patented May 23, 1922.

Application filed June 16, 1921. Serial No. 477,919.

To all whom it may concern:

Be it known that I, JOHN HJALMAR LINDROOS, a citizen of the United States, residing in Brooklyn, in the county of Kings 5 and State of New York, have invented certain new and useful Improvements in Ship Structures, of which the following is a full, clear, and concise description.

My invention relates to ship structures, 10 my more particular purpose being to strengthen the hull or analogous body member of the ship by bracing the same either internally or externally, or both internally and externally, in such manner as to render 15 the structure as a whole exceedingly strong and yet having a proper amount of flexibility.

Stated more specifically, my invention 20 contemplates a hull for a ship, barge, boat or analogous vessel, made up in part of boards, planks, staves or the like, arranged somewhat after the manner of staves in a barrel, and so arranged that they become 25 tighter relatively to each other as pressure is applied to them by the water in which the hull floats, as well as when they are forced radially inward by mechanical means constituting a part of my invention.

My invention further comprehends various 30 details of construction more or less remotely associated with the hull and its connections.

Reference is made to the accompanying 35 drawings forming a part of this specification, and in which like reference characters indicate like parts throughout the several figures.

Figure 1 is a cross section through my improved device, and is taken upon the line 40 1-1 of Figure 2, looking in the direction indicated by the arrows.

Figure 2 is a fragmentary plan view of the hull.

Figure 3 is a cross section somewhat similar 45 to Figure 1, but showing a form of my device differing from that contemplated by Figure 1.

Figure 4 is a fragmentary section, upon a larger scale than that contemplated by Figure 3, and showing a detail of the construction 50 of the mechanism shown in Figure 3.

I will first describe the form of my invention contemplated by Figures 1 and 2.

The hull as a whole is shown at 5, and is 55 here shown as floating in water 6.

The hull is made up mostly of boards 7, each having in cross section the form of a stave, the hull as a whole having the general curvature indicated, or being circular or elliptical, as desired. 60

Incorporated within the structure of the hull and extending along the top thereof are stringers 9, 10, held together by bolts 11—that is, each bolt 11 extending through a stringer 9 and a stringer 10. The hatch 65 doors appear at 12, and may be opened and closed in the usual or any preferred manner.

The hull carries a narrow deck 13, of considerable length and having the general form of a running board, interrupted at intervals by the hatch doors. Extending upwardly from the deck 13 are standards 14, which may constitute parts of a superstructure to be carried by the hull. 70

The hull carries a number of stringers 15, 75 serving to some extent as keels, and which I conveniently designate as keel stringers.

Located within the hull, and disposed near the bottom thereof, is a flooring 16, serving as a deck. 80

Disposed centrally within the hull is a brace plate 17, made preferably of metal. Radiating outwardly from this brace plate are a number of tie rods 18, each made in two parts connected by a turnbuckle 19. 85 Each tie rod is swiveled to a stirrup 20, the latter being secured directly to the inner surface of the hull. The inner ends of the tie rods are secured to the brace plate 17 by means of rivets 21, as indicated in Figure 1. 90

Whenever the turnbuckles are tightened, the boards 7 are forced inwardly and thus crowded together, like the staves of a barrel. To the extent that the pressure of the water 95 6 is exerted upon the boards, they are forced inwardly and thus crowded together, so that the water pressure has a tendency to act in the manner of the tie rods, to the extent at least of tightening the boards, like the staves of a barrel whenever the latter 100 are pressed radially inward. This is a feature of considerable importance especially in instances where the hull sits deep in the water or where it is completely submerged. 105

My improved hull is thus peculiarly adapted for complete submersion, because its construction is such that the increased water pressure, due to submersion, serves as a means for crowding the boards 7 together 110

edge to edge, so as within reasonable limits to render the hull more completely watertight than would otherwise be the case.

In the form shown in Figures 3 and 4, I place on the outside of the hull a number of band sections 22, 23, 24, each provided with outwardly-turned end portions 25, 26, the end portion 25 of one section being contiguous to the end portion 26 of the next contiguous section, and connected therewith by a bolt 27. The several band sections 22, 23, 24, thus connected together, constitute a composite band more or less analogous to a barrel hoop. The band may be virtually expanded or contracted by loosening or tightening the bolts 27. When the band is thus contracted it grips the boards 7 tightly together, the action being somewhat analogous to that of gripping a barrel tightly by tightening the hoops thereupon. The composite band encircling the hull co-acts with the tie rods 18 and parts immediately associated therewith, for the purpose of forcing the boards 7 together edgewise in the manner above described, and for the purpose indicated.

The arrangement and action of the drift bolts 8 may be readily understood from Figure 4. Each drift bolt is forced through at least two thicknesses of the boards 7; that is, through two of the boards, edge to edge; and the drift bolts are staggered, as indicated by full and dotted lines in Figure 4, and thus distributed to better advantage.

While I show only a single brace plate and only one of the composite bands used for encircling the hull, it will be understood that any reasonable number can be employed.

I do not limit myself to the precise mechanism shown, as variations may be made therein without departing from my invention, the scope of which is commensurate with my claims. Neither do I limit myself to any precise use to be made of my improved hull, as obviously it can be used for many kinds of vessels, including ships, boats, barges, buoys, submarines and other submersible craft, and in fact in almost all relations where a hull can be employed.

Having thus described my invention, what I claim as new and desire to secure by Letters Patent is as follows:

1. In a device of the character described, a hull comprising a number of boards fitted together edge to edge and secured together in the proximate form of a cylinder, a plurality of tie rods connected with said cylinder and extending radially inward therefrom, and a brace plate connected with said tie rods at the inner ends thereof.

2. A hull for ships and the like, comprising a number of boards fitted together edge to edge and formed into the general proximate form of a cylinder, a band girdling the substantially cylindrical member thus formed, a plurality of tie rods connected with the interior of said cylinder and extending radially inward, a brace plate to which said tie rods are secured, and means controllable at the will of the operator for virtually lengthening and shortening said tie rods.

3. A hull for ships or the like, comprising a number of boards fitted together edge to edge and formed into a hollow member having the general proximate form of a cylinder, a brace plate located within said hollow member, tie rods secured to said hollow member and extending radially inward therefrom and connected to said brace plate so as to support the latter, a band girdling said hollow member, and means controllable at the will of the operator for tightening said band.

4. A hull for ships and the like, comprising a number of boards fitted together edge to edge and formed into a hollow member having the general proximate form of a cylinder, a brace plate located within said hollow member, tie rods secured to said brace plate, a turnbuckle for each tie rod, a stirrup swiveled to each tie rod, the several stirrups each being secured rigidly within said hollow member, and a metallic band encircling said hollow member.

5. A hull for ships or the like, comprising a plurality of boards each having in cross section the form of a sector, said boards being fitted together edge to edge so that the several consecutive sectors form a curved wall, the boards being secured together, a plurality of stirrups each secured to the inner surface of the curved wall, a plurality of tie rods each connected with one of said stirrups, each tie rod being provided with a turnbuckle whereby it may be virtually lengthened or shortened, and a brace plate common to all of said tie rods, said tie rods being secured to said brace plate and radiating therefrom.

JOHN HJALMAR LINDROOS.
